DISPENSING TUBE

Samuel A. Stone, 25 Mumford Road, New Haven, Conn.

Filed Dec. 10, 1962, Ser. No. 72,802

Term of patent 14 years

(Cl. D58—17)

FIG. 1 is a top perspective view of a dispensing tube embodying my new design, with the closure in open position;

FIG. 2 is a fragmentary top rear perspective view thereof with the closure in closed position and wherein the flexible strap joins the cap at the flange;

FIG. 3 is a fragmentary side elevational view thereof; and

FIG. 4 is a fragmentary side elevational view showing a modified form of my new design wherein the closure of the configuration shown is attached to the tube by a flexible strap.

The characteristic features of my design reside in a cylindrical dispensing tube wherein the closure of the configuration shown is attached to the tube by a flexible strap as shown.

This application is a continuation in part of my earlier-filed, co-pending application, Serial No. D. 69,684, filed April 12, 1962, now abandoned.

I claim:

The ornamental design for a dispensing tube, as shown and described.
